[57]

ABSTRACT

A safety latch for a cabinet door is disclosed which includes two plastic members affixed respectively to the door and to the jamb, advantageously by means of a foam-type pressure sensitive adhesive. The portion of the combination latch affixed to the door includes a main body having a flush mounted and preferably integrally die cast plastic flap or tab an end of which is releasable by inwardly directed adult finger pressure. Release of the tab exposes a recessed well into which a finger may be inserted to release the hook-like projection of the first member from a shoulder of the main housing. This release permits the cabinet door to be opened. The cabinet is relocked by urging the portion of the combination latch that is on the door against the portion affixed to the jamb. The flap of the catch is then closed and provides a completely flush surface thus preventing access to the cabinet contents except by children who lack sufficient power and digital dexterity to manipulate the flap and catch mechanism.

CABINET SAFETY LATCH

BACKGROUND OF THE INVENTION

This invention relates to door latches and, more particularly, to a safety latch for cabinet doors found in and about the household. Recent federal regulations have made mandatory the use of special types of bottle closures for materials whose contents may be dangerous if carelessly taken or employed otherwise than carefully in accordance with set prescription. Even the ubiquitous aspirin bottle is now required to be protected by a cap that cannot be casually removed by an adult and which requires an amount of dexterity and a degree of intellectual concentration beyond that exhibited by children of tender years.

While these safety minded efforts are certainly commendable, no effective steps have yet been taken to exclude children from those areas of the home which contain poisons, sharp instruments, corrosives or other dangerous instrumentalities. In the average under-sink cabinet of the American home will usually be found one or more of the following: household bleach containing chlorine compounds, drain cleaners containing lye, automatic dishwasher detergent containing strong phosphate compounds, steel wool, lemon oil furniture polish, powdered cleanser containing ground glass and sophisticated chlorine liberating chemicals, etc. The under-sink kitchen cabinet is easily within reach of the small toddler at the very time when his curiosity and mobility greatly exceed his discretion. Yet, nothing has been done to place a lock on this particular "barn door".

Of course, the concerned parent may simply do just that. It would require no breakthrough of technology to drill through the cabinet door and install a simple hasp and padlock. Yet we are aware of no household where this has been done. It is not because parents lack genuine concern for the safety of their children, it is simply because in the words of C. S. Lewis "Crisis-feeling . . . is essentially transitory." A hasp and a padlock are not the sort of items that the housewife and mother buys despite the fact that it may be within her everyday experience to see her toddler fingering the under-sink cabinet latch and making tentative explorations of its intriguing contents. And even if, should the tired husband come home from the office and be met at the door, not with a martini and slippers, but with the demand that he forthwith fetch his tool box and affix the prior art hasp and padlock to the cabinet door before sitting down to supper, still, other considerations apply to deter the fruition of the plan. The conventional hasp and padlock is not only inconvenient to install, it is also unsightly in appearance. A lock requires the use of a key or the running of a combination. The delay and inconvenience of each of these means that even if such a device is installed, it will, after an initial and perhaps only a ceremonial usage, be left unlocked. The need, therefore, is for a safety latch that is easy to install, preferably without the use of any tools and which is fast and convenient to operate requiring neither a key nor the manipulation of combinational tumblers.

SUMMARY OF THE INVENTION

The foregoing and other objects of our invention are achieved in one illustrative embodiment of our safety door latch which includes a first hook, toggle or bayonet-like member affixed to the stationary part of the

cabinet frame or door jamb and a second member mounted on the outer moving surface of the door which is adapted to cover and engage the first member when the door is closed. The second part of our door latch which, advantageously, may be manufactured of plastic includes a housing having a recess for receiving on its underside the toggle, hook or bayonet-like first member. The housing includes a cover flap which is flush with the external surface of the housing and which can only be opened by an adult having a greater than a predetermined amount of physical strength in his fingers. Advantageously, this predetermined amount may be adjusted during manufacture to coincide with the recommendations of the federal regulations governing poison containers, etc., such as those regulations promulgated by the Federal Food and Drug Administration.

The cover flap of our door latch is similar in theory of operation to the cover flap of the poison bottle closure shown in G. N. Pettersen U.S. Pat. No. 3,419,198 issued Dec. 31, 1968. In accordance with our invention, however, the cover flap is part of an elongated housing affixed to the outer surface of a cabinet door and when the cover flap of our invention is opened, a cavity is exposed in the housing which permits a finger to be inserted to release the engagement of the first or stationary member of our combination latch. In the preferred embodiment of our invention, the first and second members of our combination latch are affixed to the door jamb and to the door surface, respectively, by the use of a pressure-sensitive adhesive thereby eliminating the need for the user to employ any installation tools. In the preferred embodiment of our invention, the flush cover flap and the housing which comprise the second member of our combination safety latch are die cast as an integral assembly, the hinge portion of the cover flap being comprised of a relatively thin flashing or web section between the comparatively heavier cross-sections of the tab and of the housing. Beneath the tab in a well provided in the housing is a pivot bar or fulcrum against which the tab may be urged when pressure is applied by the finger to the external surface of the tab at a point between the hinge and the location of the pivot bar. Since the pivot bar beneath the flap is invisible when the flap is closed, a suitable index mark is placed on the exposed surface of the tab to show where pressure is to be applied. The application of pressure in sufficient amount, approximately four pounds, causes the tab to bend inwardly between the hinge and the fulcrum and outwardly beyond the fulcrum thereby releasing the cantilevered end of the tab from the recessed lip of the housing. The end of the tab is then made accessible to the fingers and the tab may be fully opened to expose the recess into which the first member of the combination safety latch has been entered through the underside of the main housing.

According to our invention, the hook or toggle-like first member (when exposed to view by opening the flap) may be bent away from an engaging shoulder that is integral with the second member housing to release the latch thereby permitting the cabinet door to be opened. In one embodiment, the first member is fabricated having a resilient plastic web-like section that serves as a spring-like catch such that it may be bent under finger pressure away from the second member and then return itself to its original shape. Alternatively, the first member may be made in four pieces in

cluding a yoke, a tongue, a hinge-pinion and a spring that normally urges the tongue into engagement with the shoulder of the second member.

BRIEF DESCRIPTION OF THE DRAWING

The foregoing and other objects and features of our invention may become more apparent by referring now to the drawing in which:

FIG. 1 shows a perspective and partial sectional view of the safety latch of our invention affixed to a cabinet door and its door jamb in which the flap has been opened to expose the pivot bar, the recessed well and one version of the catch;

FIG. 2 shows a top view of the latch;

FIG. 3 shows a side view of the latch and catch members in engagement;

FIG. 4 shows the side view of an alternative embodiment of our invention employing a single piece catch; and

FIGS. 5, 6, and 7 show three different types of cabinet door constructions with the appropriate safety latch mounted of our invention.

GENERAL DESCRIPTION

Referring now to FIG. 1 there is shown the safety door latch of our invention. Affixed to door 1 is the main body 3 of our safety door latch which is positioned on door 1 so that its end 3' overhangs the edge 1' of the cabinet door. The under surface of main body 3 which is in contact with door 1 is advantageously provided with a urethane foam pressure sensitive adhesive 3''. Foam-type pressure-sensitive adhesives are preferred inasmuch as they readily conform to the surface imperfections of a cabinet door once the door has been cleaned using commonly available rubbing alcohol or conventional household spray cleaner. The pressure-sensitive adhesive may have a thickness of approximately 1/32 of an inch. Body 3 has a depth D so that it can receive within its aperture 4 the tongue 6 of the catch member 7 which is affixed to the door jamb 2 of the cabinet. Aperture 4 is normally hidden from view by flap 8 which is shown in the open position. Flap 8 is hinged at 9 to the upper surface of main body 3 and includes a lip 10 which engages recess 11 of main body 3 when flap 8 is closed.

Main latch body 3 includes a well 12 into which flap 8 may be partially depressed by finger pressure applied to point 15. To facilitate the bending of flap 8, its under surface may include a notch 16. The well 12 of body 3 includes an integrally cast pivot mound or bar 20 whose apex is positioned beneath the top surface 19 of member 3 a sufficient distance to allow for the thickness t of member 8. When flap 8 is closed, notch 16 lies between hinge 9 and the apex of pivot mound 20, but is advantageously closer to the apex of mound 20 than to hinge 9. Pressure point 15 on the outer, visible surface of flap 8 is located between notch 16 and hinge 9 but is advantageously located closer to notch 16 than to hinge 9. Pivot mound 20 includes a shoulder 21 for receiving the projecting mushroom head 6' of catch 6.

Referring now to FIG. 2, there is shown a top view of the main body 3 with the hinged flap 8 fully opened exposing well 12 and aperture 4. Flap 8 is hinged to the main body 3 at 9. Hinge 9 advantageously may be produced during die casting of the main body by providing for a thin resilient section or flashing of the plastic being cast. Between the aperture 4 and well 12 is pivot

mound 20 having a shoulder 21 adjacent aperture 4. The top surface 19 of body 3 may advantageously be provided with a small bead 19', the purpose of which is to discourage the insertion of a finger nail or other sharp instrument between the edges 8' of flap 8 and the peripheral surfaces 12' of well 12 by a child or other individual attempting to defeat the operation of the device. When flap 8 is closed, edges 8' will abut edges 12' very precisely and it is preferred that there be less than about 0.005 inch clearance.

In FIG. 3, a side view of the main body 3 and catch 6 is shown wherein the hook portion 6' of catch 6 has engaged shoulder 21 of main body 3. In this position, the cabinet door is still locked to main body 3 although flap 8 is shown in the fully opened position. To release the latch, a finger is inserted in thumb recess 6'' and the catch member 6 is rotated to the left about pinion axis 25.

The under surface 3'' of main body 3 as well as the under surface 7'' of catch member 6 is provided with a pressure-sensitive adhesive which advantageously may be of the foam type. Urethane foam pressure-sensitive adhesives having a thickness of approximately 1/32 of an inch have been found to be satisfactory for use on normally smooth cabinets found in the average kitchen. Rougher textured cabinet surfaces may require a somewhat thicker foam, the increased thickness thereof compensating for the greater degree of surface irregularity.

Catch 6 is normally urged into engagement with shoulder 21 by flat spring 23, one end of which is secured to the base of trunion 7. When flap 8 is closed, button 18 on its under side engages thumb recess 6'' in catch member 6 further locking it into engagement with shoulder 21 and thereby providing an additional protection against inadvertent opening of the door 1.

FIG. 4 shows a side-view of the left-hand portion of main body 3 in engagement with an alternative embodiment of a catch 41. Catch 41 includes a projecting mushroom head 42 which engages shoulder 21 of main body 3. The mushroom head also includes a thumb recess 43 similar to thumb recess 6'' of the embodiment of FIG. 3. Catch member 41 is advantageously made of nylon or other highly spring-like plastic material and is fashioned to have a reduced cross section web portion 44 about which flexure of mushroom head 42 may take place when appropriately urged by the finger of an adult inserted into finger guide 43.

FIGS. 5, 6, and 7 show three different types of commonly occurring door and jamb arrangements. FIG. 5 shows a top view of an overlapping door and jamb fitted with the safety latch of our invention in somewhat the same manner as the arrangement of FIG. 1. FIG. 6 shows the top view of an abutting door and jamb arrangement in which the main body 3 of our catch is advantageously spaced out from the door by means of a spacer 3-1 to allow for the greater displacement of catch 7 from door jamb 2'. FIG. 7 shows a semi-lap type of door and door jamb arrangement which is accommodated by the use of a somewhat thinner spacer 3-2 than was required in FIG. 6.

It will be apparent that instead of using pressure-sensitive adhesives, the main body 3 and catch member 6 or 41 may be affixed to the door and jamb surfaces by means of conventional screws or bolts. However, it is thought that for the household market, the use of pressure-sensitive adhesive will facilitate the use of our

safety latch by the average home owner or housewife who may not be familiar with the use of tools. Numerous other modifications may be made by those skilled in the art without, however, departing from the spirit and scope of our invention.

What is claimed is:

1. A safety catch for locking together two members comprising

a hook member mountable to one of said members, a main plastic body affixable to the other of said members and having an aperture therethrough for receiving said hook member,

said main body having a shoulder extending into said aperture for engaging said hook member and a flush fitting cover flap integrally die cast with said main body for hiding said aperture and said hook member from view, said flap being hinged to said main body by a thin plastic flashing section.

2. A safety catch according to claim 1 wherein said main body is provided with a well beneath said cover flap into which said cover flap may be depressed to release an edge thereof opposite said hinged-flashing section.

3. A safety catch according to claim 2 further including a fulcrum bar positioned in said well beneath said cover flap against which said cover flap may be urged to facilitate the release of said edge of said flap.

4. A safety catch according to claim 3 wherein a portion of said well opposite said hinge is provided with a recess and wherein said cover flap is provided with a mating lip to engage said well recess.

5. A safety catch according to claim 4 wherein said cover flap is provided with an index mark on the external surface thereof intermediate said hinge and the

apex of said fulcrum bar.

6. A safety catch according to claim 1 further comprising a pressure-sensitive adhesive coating applied to the underside of said main body.

7. A safety catch according to claim 6 wherein said hook member includes a pressure-sensitive adhesive coating applied to the underside thereof.

8. A safety catch according to claim 7 wherein said hook member includes a base, a thin resilient section 10 and a mushroom head portion at the end of said thin section, said resilient section having a spring-like characteristic adapted to urge said mushroom head into engagement with said shoulder in said main body aperture.

9. A safety catch according to claim 1 wherein said hook member includes a base member defining a pair of trunions, a hook-shaped catch member fitted between and pivotably secured to said trunions and a spring for biasing said catch member into engagement 20 with said shoulder.

10. A safety catch according to claim 9 wherein said hook member includes a finger recess whereby catch member may be released from engagement with said shoulder when said cover flap is opened.

11. A safety catch according to claim 10 wherein a surface of said hook member and a surface of said main body have applied thereto a pressure-sensitive adhesive coating.

12. A safety catch according to claim 11 wherein said cover flap includes a button on its underside for engaging said hook member finger recess when said flap is closed thereby locking said hook member against motion.
